UNITED STATES PATENT OFFICE

129,303

DESIGN FOR A HEATING RADIATOR

Charles W. Good, Erie, Pa., assignor to Weil-McLain Company, Erie, Pa., a corporation of Delaware

Application June 12, 1940, Serial No. 92,947

Term of patent 14 years

To all whom it may concern:

Be it known that I, Charles W. Good, a citizen of the United States, residing at Erie, in the county of Erie and State of Pennsylvania, have invented a new, original, and ornamental Design for a Heating Radiator, of which the following is a specification, reference being had to the accompanying drawing, forming a part thereof.

The figure is a perspective view of a heating radiator showing my new design. The opposite side and end not shown have substantially the same appearance as the side and end shown.

I claim:

The ornamental design for a heating radiator, substantially as shown and described.

CHARLES W. GOOD.
